UNITED STATES PATENT OFFICE.

CHARLES S. UPTON, OF NEW YORK, N. Y.

LAMP.

SPECIFICATION forming part of Letters Patent No. 381,042, dated April 10, 1888.

Application filed March 25, 1887. Serial No. 233,418. (No model.)

To all whom it may concern:

Be it known that I, CHARLES STANFORD UPTON, a citizen of the United States, residing at New York, in the county and State of New York, have invented certain new and useful Improvements in Lamps, of which the following is a specification.

My invention relates to an improvement that is adapted to be used in connection with central-draft lamp-burners in general, but is more practically applicable to what is known in the trade as the "Rochester lamp," and it is in connection with this lamp that I will show and describe it.

My invention consists in a short perforated sleeve or collar fitting around the upper end of the inner wick-tube, having a horizontal inwardly-projecting flange extending over the top of the latter, so that the oil, when it leaves the wick, instead of creeping by means of capillary attraction over the top of the inner wick-tube, will be absorbed through the perforations in the aforesaid sleeve or collar, and thence pass down on the outside of the wick-tube and back into the oil-chamber.

Referring to the accompanying drawings, which form a part of this specification, Figure 1 is a vertical section of a portion of what is known in the trade as the "Rochester lamp."

Fig. 2 is a bottom view of the perforated sleeve or collar. Fig. 3 is a perspective view of the perforated sleeve or collar.

A is the oil-chamber of a Rochester lamp, and W is a cylindrical wick extending down into the oil-chamber, I being the inner wick-tube, having an annular depression, i, on the outside, forming an annular shoulder, i', on the inside thereof, and O the outer wick-tube, which guides and holds the wick W.

C is a collar, which encircles and retains the wick, and R is the wick-raiser, for the purpose of raising and lowering the wick when desired.

T is the perforated thimble for spreading and equalizing the air-currents which come up in the inner wick-tube, I, supported on the shoulder i' of the latter, having bosses or outward projections t. Between the thimble and

wick-tube is thus formed the annular air-chamber t'. Arranged upon the outside of the inner wick-tube, I, is a sleeve, S, which sleeve is provided with perforations s, as shown in the various figures, and it has a small inwardly-projecting flange, F, which rests upon the top of the interior wick-tube, I. 55

When the wick becomes saturated and tends to give off any oil from its inner surface, it will be absorbed through the perforations s of the sleeve S, from whence it will flow down and upon the outside of the inner wick-tube, I, and back into the oil-chamber. If, however, any oil reaches the top of the sleeve S on the inside of the latter, it will flow around beneath the flange F and between the sleeve S and the outside of the inner wick-tube, and thence back into the oil-chamber A. Heretofore in lamps of this kind where this perforated sleeve has not been employed there has been a tendency on the part of the oil to creep over, in small quantities, the top of the inner wick-tube, thus escaping outside of the lamp, thereby causing more or less trouble and annoyance. My invention removes this objection and reconveys, as above stated, all the oil that has left the wick back into the chamber without permitting any of it to escape. 75

Having thus described my invention, what I claim as new therein, and desire to secure by Letters Patent, is—

The combination, with the inner wick-tube, I, and the outer wick-tube, O, of the short sleeve S, fitting around the upper end of the inner wick-tube inside the wick-space and having a horizontal inwardly-projecting flange, F, resting on the top of the inner wick-tube, 80 and formed with perforations s, the said perforations providing passages for conveying the surplus oil from the upper part of the wick-space to the surface of the inner wick-tube, and the flange preventing the oil from 85 overflowing the top of the inner wick-tube, 90 substantially as described.

CHARLES S. UPTON.
